Specification of Letters Patent

Patented Oct. 6, 1914.

Application filed June 14, 1905, Serial No. 265,250. Renewed March 2, 1914. Serial No. 822,074.

To all whom it may concern:

Be it known that I, GEORGE E. LYNCH, a citizen of the United States, residing at Columbus, in the county of Franklin and State of Ohio, have invented certain new and useful Improvements in Mining-Machines, of which the following is a specification, reference being had therein to the accompanying drawing.

10 This invention relates to improvements in reciprocating tools, such, for example, as pick mining machines. It has long been well known that electric motors have been operated with considerable loss and with low 15 efficiency when combined with powerful reciprocating tools in which the load is intermittently varied.

The principal object of my invention is to provide such a construction of parts that 20 an electric motor can be used with more efficiency and to greater advantage than has been the case in motor driven tools of this class as heretofore constructed, and to this end I have sought to maintain the load on 25 the motor substantially constant although the work done by the tool proper is intermittent.

In the preferred construction by which the 30 above object is attained, I combine with the motor an air compressor and utilize the air compressed by the motor to drive the tool, the air after compression being suddenly released against a piston connected with the tool so as to snap the latter forward. Furthermore the construction is such that the 35 effort of the motor is almost continuously applied to the compression of the air, that the power transmission devices between the motor and compressor piston are designed 40 to give the motor a mechanical advantage that increases at substantially the same rate as does the resistance offered by the air and that the energy of the motor is absorbed by the fly wheel devices during the brief intervals in which the tool is snapped forward. Clearly these conditions are adapted to give 45 a result approaching the ideal, viz., a constant motor effort.

In the accompanying drawings I have 50 illustrated an apparatus embodying my improvements which will be readily understood from the description below.

Figure 1 is a side elevation of a coal mining machine constructed in accordance with 55 my invention, the near side plate or wall of the

casing being removed, and certain of the parts shown in section. Fig. 2 is a plan view, parts being shown in section. Fig. 3 is a central, vertical, longitudinal section of a part of the machine, including the air cylinder and contiguous parts, this view being on a larger scale than Figs. 1 and 2. Figs. 4 and 5 are face views of the opposite sides of one of the operating disks C.

The machine shown is of the class of undercutting pick machines used in the mining of coal. It comprises a main frame 20 mounted on two truck wheels 30, the frame parts being preferably constructed and shaped to serve as a casing or housing as 60 well as a support for the operative parts.

At the rear of the machine is mounted the electric motor A, the armature shaft of which has the prime pinion 1 meshing with the gear wheel 2 secured to an intermediate 65 shaft which extends across the machine and carries a pinion 3. The latter engages with the wheel 4 on the crank shaft H also mounted in sockets 24 carried by the side pieces or casing of the main frame transversely of the 70 machine and parallel to the armature shaft and the intermediate shaft. The crank shaft has two crank pins I, I.

D, D are links pivotally connected to the reciprocating tool, one on one side of the 75 longitudinal axis of the tool and the other on the other side. They are pivoted to the crosshead part K into which are fitted the stock or shank L and the rod J, the shank L carrying the tool socket M and the rod J being connected to the piston parts to be described. These links D are parts of a toggle 80 system, their companion links being indicated by E, E, one of the links D being pivoted to one of the links E. The links E are 85 at their fulcrum ends mounted in bearings consisting of studs or bosses 21 formed on the side walls of the frame or casing.

C, C indicate the parts which impart power to the toggle system. They are shown 90 as formed of disks which have stud shafts or hubs which are mounted in the aforesaid bearings that support the links E. Each of these disks has a rib or projection at z, and another at z', these being adapted to engage 95 with and bear against the toggle links E.

The crank pins I, I above referred to are connected to the disks C, C respectively by means of pitmen F. The parts are so related and are of such dimensions that when 100

110

the crank shaft H is rotating it rocks but does not rotate the disks C, C.

The rod J which as above stated forms one of the series of parts which constitute the stem of the reciprocating tool is connected to a piston N which is fitted to a cylinder B, the cylinder being somewhat longer than the stroke of the tool. When the parts at J and K are drawn backward the piston N is 10 pushed toward the rear end of cylinder B and compresses the air therein contained. When the tool is released from the parts connected with the motor the expansion of the air drives the piston N and tool connected therewith forward and a blow is imparted.

The drawing backward of the tool and of the piston, and their quick release are effected as follows: When the crank shaft H is 20 being rotated by the armature the pitmen F will draw the links E backward from the position shown in Fig. 1, and these in turn will draw the links D, the tool and the piston backward with a corresponding 25 movement. The links continue moving in this direction until the radius of each link E reaches and has passed beyond the horizontal plane of their fixed axes. As soon as they have thus passed a little beyond this 30 plane, which occurs, at or a little after the instant of the greatest compression of the air, these links E rapidly pass from the shoulder at Z around to the shoulder or stop Z', the positions thus taken by the links 35 E and connected links D being indicated by the dotted lines E' and D' in Fig. 1. Thus by reason of the loose or lost motion connection between the toggle lever system and the driving shaft, the links E, during this 40 part of the cycle, are released from active connection with the motor driven parts. And while they are making this free movement the piston is released from any holding devices and under the expansion of the 45 air in the cylinder B moves quickly forward as above described.

Approximately at the moment the piston and tool start forward on their free stroke, the connecting rod F is in its rearmost position and starts immediately to move forward. By this latter movement the disks C are rocked in the opposite direction, and they in turn bring the links E backward again and also the tool and piston N, this 50 continuing until the links E have got above the plane of their fixed axes when they are released a second time and the tool and piston again moved forward under the expansion of the air; and thus the cycle is 55 repeated indefinitely.

It is clear that the effort of the motor, except during the brief interval in which the piston and tool are snapped forward, is expended in forcing the piston back to 60 compress the air. The brief interval re-

ferred to is bridged over by the fly wheel action of the parts 4, I' and I², and therefore the resistance to the effort of the motor is continuous. And not only is it continuous but, also except for a comparatively slight fluctuation during the forward snap of the piston and tool—and even this can be practically eliminated by using a sufficiently heavy fly wheel,—the effort of the motor is substantially constant. This result I attain by means of the toggle lever system in combination with the air cylinder and piston. I have found that when the parts of a toggle lever system move from the position of minimum to that of maximum advantage, the rate of change of the mechanical advantage is at all times approximately the same as the rate of increase of the resistance of air subjected to compression by the toggle levers. It is clear 85 that the gearing which I have designed to transmit power from the motors to the toggle levers gives the latter a range of movement such as that referred to, and I therefore attain the desired result, viz., a 90 practically constant load on the motor.

While, as now advised, I prefer a mechanism comprising the toggle lever system and the air cylinder and piston for attaining the desired end, it should be understood that I do not limit my invention to such devices. On the contrary my invention contemplates the use of any suitable resilient means for snapping the tool forward in combination with transmission devices between the tool 100 and motor adapted to give the motor a mechanical advantage that varies throughout the retraction of the tool in approximately the same proportion as does the resistance of the resilient means.

I have used the expression "mechanical advantage" as having a generic meaning broader than that of the word leverage. That is to say, the expression is used to describe what would properly be described by the word leverage if only a lever or levers were employed to connect the motor to the tool elements. The expression is properly applicable to a motor or other driver which is connected to a driven device by any of the mechanical powers.

I so arrange the piston N, the cylinder B and adjacent parts that there shall be an air cushion chamber ahead of the piston when it makes its forward stroke. To insure that there shall be air of the proper amount and pressure in this chamber at each stroke I form a port U in the wall of the cylinder at the proper point which port is passed by the piston as it moves forward 120 so that the inclosed body of air can be compressed and serve as a cushion, this preventing shock in case the tool fails to strike or perform work.

As there is liability for the air in the 130

main chamber of the cylinder B to fall below the desired volume and pressure, as by leakage, I prefer to provide mechanism for keeping up a predetermined pressure. O indicates a piston or plunger mounted in a compressor cylinder O'. The plunger is reciprocated by an eccentric Q on the crank shaft H. P is an inlet port, and at R there is a spring-held valve. By these devices a body of air can be kept under pressure in the reservoir W, and this air can be admitted to the cylinder B through a valve at X whose retaining devices can be so set that the valve will open as soon as the difference between the pressure in the cylinder B and that in the reservoir W has reached the predetermined point.

As the reciprocations of the piston and the blows of the tool create more or less vibration which is harmful for the motor I have devised a novel mounting for the drill engine. The motor, together with its armature shaft and the intermediate shaft are mounted in plates or frame pieces 23 which are pivotally or flexibly connected to the rest of the structure, the axis of the crank shaft H being the axis of the union. The main frame or the frame which supports the cylinder, the piston and the tool can vibrate independently of the motor frame, and vice versa. To provide a resilient abutment between them I employ springs at G which bear in one direction against the tool frame and in the other direction against the motor or motor frame, these being held in place by bolts G'.

What I claim is:—

1. The combination of a frame, a reciprocating tool mounted on the frame, a piston connected to the tool, an air compression cylinder in which said piston works, a toggle lever system connected to and adapted to retract the tool and piston, an electric motor mounted on the said frame, and power transmitting devices between the motor and toggle lever system adapted to convert the continuous rotation of the motor into a reversing or oscillatory movement of the toggle levers, said transmission devices comprising parts having a lost motion connection.

2. The combination of a frame, a reciprocating tool mounted on the frame, means comprising resilient means tending to force the tool forward, a toggle lever system connected to and adapted to retract the tool, an electric motor mounted on the frame, and

power transmitting devices between the motor and toggle lever system adapted to convert the continuous rotation of the motor into a reversing or oscillatory movement of the toggle levers, said transmission devices comprising parts having a lost motion connection.

3. In an apparatus of the character set forth, the combination of a frame, a reciprocating tool mounted on the frame, means comprising resilient means for forcing the tool forward, an electric motor mounted on the frame, and power transmission devices between the motor and tool, for retracting the tool against the tension of the said resilient means and then releasing it, said transmission devices being constructed and arranged to transmit the power of the motor with a mechanical advantage that is variable throughout the retraction of the tool in approximately the same proportion as the resistance of the said resilient means.

4. The combination of a frame, a reciprocating tool mounted on the frame, a piston connected to the tool, an air compression cylinder in which said piston works, an electric motor mounted on the frame, means comprising a toggle joint for transmitting power from the motor to the piston and tool to retract the latter against the pressure of air, and means whereby the driving element of said toggle joint is limited to a movement of approximately ninety degrees from its position corresponding to maximum mechanical advantage.

5. The combination of a frame, a reciprocating tool mounted thereon, means comprising resilient means acting to force the tool forward, a toggle lever system having one arm mounted to swing about a fixed axis, and another arm connected to the tool, whereby the swinging of the first mentioned arm effects the retraction of the tool, an electric motor mounted on the frame, a disk mounted on the said fixed axis having a lost motion engagement with the first mentioned swinging toggle arm, and power transmission means for converting the continuous rotation of the motor into a reversing or oscillatory movement of the said disk.

In testimony whereof I affix my signature, in presence of two witnesses.
